POUNCING MACHINE AND METHOD OF
POUNCING

Paul Schultze, Danbury, Conn., assignor to John C. Doran, doing business as Doran Brothers, Inc., Danbury, Conn.

Application July 29, 1937, Serial No. 156,330

5 Claims. (Cl. 223—20)

This invention relates to a pouncing machine and a method of pouncing, and more particularly to an improvement in the pouncing machines shown in my co-pending applications, Serial No. 5,757, filed February 9, 1935, and Serial No. 86,484, filed June 22, 1936.

Among the various methods of pouncing or finishing a felt hat are those which utilize a rotating hat block and a pouncing tool between 10 which relative motion is effected manually or mechanically. The pouncing tool usually has an abrasive surface which cuts off the nap of the hat felt and imparts a smooth relatively napless finish to the hat. Depending on the grade of 15 abrasive used and the type of felt in the hat, the finish is relatively smooth or coarse, but in either event the finish imparted to the hat by the machines and methods usually employed, while satisfactory in certain grades of hats, is unsatisfactory in other grades.

In certain types of hats the felt is formed of closely matted strands of fine fur, such as beaver for example, the loose ends of which form the nap and are cut off by a pouncing operation. 20 In some methods the cutting is done by a tool moving constantly in one direction against the hat which moves in the opposite direction. In other methods the tool and hat move in the same direction, the tool surface moving much faster than the engaged hat surface. Other methods employ a reciprocating tool to finish the rotating hat, while still other methods use a stationary tool such as a manually operated tool, contacting the rotating hat. In each instance, however, the direction of cut on the fur fiber ends is inclined with respect to the axis of the fiber so as to form a sharp point on each fiber end. This results in a finish which is not as soft or smooth as desired and often necessitates additional operations to properly finish the hat.

It is accordingly among the objects of this invention to provide a sturdy and durable pouncing machine and a practicable method of pouncing well able to impart to a felt hat a finish of 35 desirable smoothness and softness and do so in a thoroughly practical and efficient manner.

The invention accordingly consists in the features of construction, combinations of elements, arrangements of parts and in the several steps 40 and relation and order of each of the same to one or more of the others, all as will be illustratively described herein, and the scope of the application of which will be indicated in the following claims.

55 In the accompanying drawing, in which is

shown one of the possible embodiments of my invention,

Figure 1 is an elevation of one side of my pouncing machine;

Figure 2 is a vertical section of a reversing 5 switch taken along the line 2—2 of Figure 3; and

Figure 3 is a horizontal section taken along the line 3—3 of Figure 2.

Similar reference characters refer to similar parts throughout the several views of the drawing.

Referring to Figure 1, my pouncing machine comprises a base 10 in the upper part 11 of which is mounted a motor 12 having a driving pulley 13, which drives by means of a belt 14 a pulley 15 attached to one end of a rotatable hat support or spindle 16. Mounted on the end of support 16 is a hat block 17 on which may be secured a hat 18. A bracket 19 extends from the lower part of base 10 and pivotally mounts a 20 tool arm 20, which in turn reciprocably supports a pouncing tool 21, the reciprocating mechanism for which is housed in lower portion 22 of tool support 20 and is driven by motor 23. Hydraulic mechanism generally indicated at 24 pivots tool 25 support 20 about hat 18 by means of a rack and pinion 25, the tool support also being swingable toward and away from hat support 17 through the coaction of cam and roller 26. For a more detailed description of the various parts here 30 generally described, reference is made to my co-pending application Serial No. 86,484, filed June 22, 1936.

As described in my above-noted co-pending application, hydraulic mechanism 24 causes pivotal movement of pouncing tool 21 about and in contact with hat 18 in a path extending from the tip 18a to the brim 18b thereof, and thence back over the same path. During this period of contact between the hat and tool, tool 21 is reciprocating quite rapidly while hat 18 is rotating at a relatively low rate of speed. During the relative movement of the tool and the hat, felt is abraded from the hat. That is, the relatively long nap is cut off the hat's surface so as to 45 impart a soft and smooth finish thereto. More specifically, this nap comprises many minute fur fiber ends which are cut off by tool 21 at a point close to the body of the hat. Assuming that the hat is rotating in a clockwise direction, as viewed 50 in Figure 1, it should be noted that on the up stroke of tool 21 the tool moves oppositely to the hat movement, whereas on the tool's down stroke the tool and hat move in the same direction. The result of this is a severance of the fiber ends at 55

an angle to the axis of the fibers, causing many minute, sharp points which detract from the smooth, soft finish desired. To attain this desired finish, the fiber ends should be rounded or squared, rather than pointed. To this end I reverse the direction of rotation of hat 18 when tool 21 reaches the forward end, e. g. the brim 18b end of its path of movement. Consequently, as the tool retraces its path (from brim 10 to tip) the hat 18 is rotating oppositely from the direction of its rotation during the tip to brim travel of the tool. Accordingly, the predominating cut of the tool is oppositely directed and cuts off, or in effect rounds the previously sharpened or pointed fiber ends, and the desired smooth finish is achieved.

As noted above, tool 21 is pivoted about hat 18 by the hydraulically actuated rack and pinion 25. Rack 25 carries a reversing cam 26, which engages an arm 27 of a bell crank 28 when the tool reaches the end of its forward stroke at hat brim 18b. The engagement between cam 26 and bell crank arm 27 causes counter clockwise movement of the bell crank, forcing a rod 29 upwardly against arm 30 of a detent pivoted to a bracket 31 mounted on the top of a reversing valve 32. When detent 30 is tripped, a spring (not shown) enclosed in reversing valve 32 forces the valve gate (not shown) and its plunger rod 33 upwardly to reverse the direction of flow of oil to hydraulic mechanism 24. As is more fully explained in my above-noted co-pending application, this reversal causes the back-stroke of tool 21, that is, from hat brim 18b to hat tip 18a. As noted above, it is desirable during the back-stroke of tool 21 over the hat to reverse the rotation of hat 18. Accordingly, I provide a reversing switch generally indicated at 34 which is mechanically operated by valve plunger rod 33. As is more clearly shown in Figures 2 and 3, switch 34 is preferably a triple-pole double-throw switch, which is connected by any suitable circuit to motor 12 (Figure 1) which may be a three phase A. C. reversible motor or a D. C. motor. Switch 34 includes a housing formed by a pair of casings 35 and 36 (Figure 2) between which a block 37 of insulating material is disposed, the casings and insulating block being held together by suitable nuts and bolts 38 extending therethrough. Extending through and connected to insulating block 37 are terminals 39, 40 and 41, terminal 39 being a power input terminal and terminals 40 and 41 being power take-off terminals suitably connected to motor 12. Switch 34 being a triple-pole switch, terminals 40 and 41 are provided in triplicate (Figure 3). A resilient contact bar 42 (Figure 2) has one end 42a secured to terminal 39, while the free resilient end 42b of this bar extends through a hole 37a in insulating block 37 to engage resiliently a switch bar 43. Bar 43 is secured to an insulating rocker 44 mounted on a rod 45 in turn rockably mounted (see Figure 3) in journals 46 formed on casing 35. Switch bar 43 has sets of terminals 47 and 55 which are engageable respectively with terminals 40 and 41 depending upon which direction of motor operation is desired, and accordingly upon the direction in which rocker 44 is moved. A stop 48 is bolted to rocker 44 and has ends 48a and 48b which engage portions of casing 35 on opposite sides of rocker 44 to limit the extent of movement of the rocker, and accordingly prevent bending the ends of switch bar 43. A bracket 49 is clamped on an end 45a of rocker

shaft 45, this clamp also having secured between portions 49a (Figure 2) and 49b thereof, one end of a flat spring 50, the other end of which is secured as by a clamp 51 to a bracket 52 (Figure 3) secured about valve plunger rod 33. A starting lever 53 (Figure 1) when moved to the right depresses valve rod 33 to instigate traversing of tool 21 over hat 18 from tip 18a to brim 18b thereof. At the same time valve rod 33 (Figure 2) depresses spring 50 which turns rocker 44 counter-clockwise to engage switch bar contacts 55 with terminals 41. Power, accordingly, flows through terminal 39, contact bar 42, switch bar 43, contacts 55 and terminals 41 to one side of motor 12, causing operation of the motor in a direction to rotate hat 18 in a clockwise direction.

Upon upward or reversing movement of valve rod 33 upon actuation by cam 26 (Figure 1) spring 50 (Figure 2) is raised to turn rocker 44 in a clockwise direction and cause engagement between contacts 47 and terminals 40. Power accordingly flows through terminal 39, contact bar 42, switch bar 43, contacts 47 and terminals 40 to the other side of motor 12, thus to operate the motor to rotate hat spindle 16 and hat 18 in a counter-clockwise direction, during which direction of rotation tool 21 is traveling from hat brim 18b to hat tip 18a.

When tool 21 reaches the brim end of its travel, valve rod 33 is released to move upwardly as pointed out above to thus reverse the direction of traverse of tool 21 over the hat. It will now appear that the forward and reverse traverse of reciprocating tool 21 over hat 18, which rotates clockwise and counter-clockwise respectively, is effected to round or square the fur fiber ends of the nap on the hat.

My method may be summarized as follows: Hat 18 is rotated in clockwise direction during which tool 21 reciprocates and moves over the hat surface in a path from the tip to the brim thereof. Upon the tool's reaching the brim end of its travel, I reverse the rotation of hat 18 and at the same time cause the reciprocating tool to retrace its original path of movement.

It will accordingly be seen that I have provided a machine and a method for pouncing a hat which achieves the objects set forth hereinabove in a thoroughly practical and efficient manner and which imparts to the hat a finish of the desired degree of smoothness and softness.

As many possible embodiments may be made of the mechanical features of the above invention and as the art herein described might be varied in various parts, all without departing from the scope of the invention, it is to be understood that all matter hereinabove set forth, or shown in the accompanying drawing is to be interpreted as illustrative and not in a limiting sense.

I claim:

1. The herein described art which consists in rotating a hat, reciprocably engaging said hat with an abrading tool, moving said reciprocating tool over the surface of said hat in a path extending from the tip to the brim thereof, reversing the rotation of said hat when said tool reaches the brim end of its path of movement over the hat, and reversing the direction of movement of said tool over said path.

2. In a machine of the nature described, in combination, a hat support, means for rotating said hat support, a traversing tool including means for traversing it over the surface of a hat

5 mounted on said hat support through a path extending from the tip to the brim of the hat, automatically actuated means for reversing the traversing movement of said tool when it reaches the brim end of its path of movement, and means for reversing the rotation of said hat support only when said tool begins its reverse traversing movement.

10 3. In a machine of the nature described, in combination, a hat support, means for rotating said hat support, a traversing tool including means for traversing it over the surface of a hat mounted on said hat support through a path extending from the tip to the brim of the hat, automatically actuated means for reversing the traversing movement of said tool when it reaches the brim end of its path of movement, and means 15 for reversing the rotation of said hat support only when said tool begins its reverse traversing movement, said last-mentioned means being operatively connected to and actuated by said automatically actuated means.

20 4. In a machine of the nature described, in combination, a column, a rotatable hat support mounted on said column, a tool support movably 25

associated with said column, a tool operatively mounted on said tool support, means in said column for effecting relative movement between said supports to effect a traversal of the tool over a hat mounted on the hat support in a path 5 extending from the tip to the brim of the hat, means for reversing the direction of said relative movement at one of its limits, an electric motor for rotating said hat support, and means associated with said second-mentioned means for reversing the direction of operation of said motor upon the reversal of said relative movement. 10 5. In a machine of the nature described, in combination, a hat support, means for rotating said hat support, a traversing tool for operating on the surface of a hat mounted on said hat support, means for effecting relative movement between said hat support and said tool through a path extending from the tip to the brim of a hat, automatically actuated means for reversing said 15 relative movement when the tool is at the brim end of said path, and means for reversing the rotation of said hat support at the time of the reversal of said relative movement. 20

PAUL SCHULTZE. 25
